UNITED STATES PATENT OFFICE

EUGENE MOREHOUSE, OF PROVIDENCE, RHODE ISLAND, ASSIGNOR TO B. A. BALLOU & CO., INC., A CORPORATION OF RHODE ISLAND

BUTTON

Application filed June 27, 1930. Serial No. 464,187.

This invention relates to a button of the type for mounting on the lapel of a coat, and has for its object to provide a construction which when secured to a piece of fabric will be prevented from rotating about the stud which extends through an opening in the fabric.

A further object of the invention is to provide a button back which will engage the fabric at a maximum distance from the stud and cause the fabric to be deflected to better secure the button thereto.

A still further object of this invention is to provide a button back which will have greater holding power with the stud of the face plate than has heretofore been usual.

A still further object of this invention is to provide a construction by which the button back will form a guard for the threads on the stud to prevent damage or wear of the end threads of the stud.

A still further object of this invention is to provide a construction formed of sheet metal or as a screw machine product which will be light and thin in construction and yet very strong to maintain the button mounted upon either heavy or sheer fabric and hold the same in position thereon.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a side view of the assembly with the button back in section;

Fig. 2 is a side view of the front plate with stud and collar mounted thereon;

Fig. 3 is a sectional view of the back member alone;

Fig. 4 is a sectional view of the assembly of the front plate and back member with the fabric gripped therebetween.

In mounting a button on a piece of fabric, such as in the lapel button hole, or in other positions on a garment, it is desirable that the button be held against rotation about the stud which extends through the fabric, that

the back member or nut provides a sufficient number of threads to ensure strength to prevent stripping of the threads in the back member, and that to provide engagement of the back of the fabric surrounding the stud be a maximum distance from the stud. I have accomplished these desirable results by providing a collar of teeth to prevent rotation of the front plate, and have provided a dome-shaped or concavo convex back with an in-turned central sleeve of a length less than the distance from the center thereof to the plane of the periphery of the back, whereby the fabric is received within the concave portion of the back member and the edges of the back member force the cloth into engagement with the teeth, and by a construction of this shape, the sleeve may be extended in length to receive a greater number of threads and yet be short of the plane of the edges of the back member to provide sufficient threads for strength and also to prevent the stud from extending through the sleeve to protrude beyond the back or outer surface of the back member to be damaged or worn by constant rubbing on the coat or clothing of the wearer; and the following is a detailed description of the present embodiment of this invention illustrating the preferred means by which these advantageous results may be accomplished.

With reference to the drawings, 10 designates the face plate which may itself be engraved, enameled or otherwise decorated with an emblem or which may have an emblem on another articulate part soldered or otherwise secured thereto. A threaded stud 11 provided with a collar is serrated on its edge to form teeth 13 is secured to the rear surface of the plate 10 by solder or any suitable means, the collar 12 being spaced from the threaded stud 11, as illustrated at 14 in Figure 4. The back member 15 is concavo convex or dome-shaped having a concavity 16 on its inner side and a convexity 17 on its outer side, and at its central portion the stock is turned inwardly as at 18 to provide a sleeve threaded as at 19 to engage the threads of the stud 11 on the face plate.

The sleeve 18 is of a sufficient length to provide a sufficient number of threads for 100

strength in gripping the stud 11 to prevent stripping of these threads when turned into binding engagement, and yet is not of a length to reach the plane 20 of the edges 21 of the back member 15, whereby these edges 21 will engage the fabric 22, as illustrated in Figure 4, and force the same into engagement with the teeth 13 and at the same time the teeth or collar 12 will cause the deflection 10 of the fabric, the same being received in the concavity 16 to securely bind it between the back member and face plate 10, as illustrated in Figure 4.

When in binding position, the stud 11 will 15 not reach the outer surface 23 of the back member, and consequently will be housed, as illustrated at 24, so that the threads of the stud are protected against damage or wear which may occur by constant movement or 20 rubbing on the fabric when worn.

While I have described certain construction forms which embody the principles of my invention, it is obvious that other desired changes in arrangement may be made within 25 the spirit and the scope of the invention as defined in the appended claims.

I claim:

1. In a button, a face plate, a stud projecting rearwardly therefrom, a separate collar 30 having a serrated edge forming teeth about said stud and secured to said face plate, a back member of a diameter greater than said collar, and means on said member for engaging said stud to force said teeth into a fabric between them and said back member.

2. In a button, a face plate, a stud projecting rearwardly therefrom, a sheet metal collar on said face plate spaced from and extending about said stud and having a toothed 40 edge, a back member of a diameter greater than said collar and concave to receive the same, means on the member for separably engaging the stud, whereby the button may be mounted in a button hole and the collar 45 will deflect the fabric from the plane of the edges of the back member into the concavity thereof.

3. In a button, a face plate, a threaded stud projecting rearwardly therefrom, a back 50 member domed to provide a hollow inner cup portion with an internally threaded sleeve extending centrally inwardly therefrom short of the plane of the edge of said back member, whereby increased threads are provided on 55 said back member for said stud and the point of engagement of said member with the fabric is spaced from said stud.

4. In a button, a face plate, a threaded stud projecting rearwardly therefrom, a back 60 member domed to provide a hollow cup portion with an internally threaded sleeve turned inwardly centrally thereof providing an opening therethrough, the dome of said back member being sufficient to prevent the stud 65 extending rearwardly from the outer surface

of said member when in engagement with the fabric, whereby the end of said stud is housed and protected against damage or wear.

5. In a button, an emblem receiving face plate, a threaded stud projecting rearwardly therefrom, a collar of circularly arranged teeth spaced from but extending about said stud, a back member, concave on its inner side and convex on its outer side and provided with an inturned central sleeve to receive said stud, said sleeve and stud having interengaging threads for securing them together. 70 75

6. In a button, an emblem receiving face plate, a threaded stud projecting rearwardly therefrom, a collar of circularly arranged teeth spaced from but extending about said stud, a back member, concave on its inner side and convex on its outer side and provided with an inturned central sleeve extending short of the plane of the edges of said member to receive said stud, said sleeve and stud having interengaging threads for securing them together. 80 85

7. In a button, an emblem receiving face plate, a threaded stud projecting rearwardly therefrom, a collar of circularly arranged teeth spaced from but extending about said stud, a back member, concave on its inner side and convex on its outer side and provided with an inturned central sleeve to receive said stud, said sleeve and stud having interengaging threads for securing them together, whereby fabric between said plate and back member will be forced into said concave portion by said collar and engaged by the peripheral edges of said back member to force the same onto said teeth. 90 95 100

In testimony whereof I affix my signature.
EUGENE MOREHOUSE.
